UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,951, dated April 8, 1884.

Application filed July 23, 1883. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets or similar 10 fabrics; and it consists in the novel configuration and grouping of figures herein specifically shown and claimed.

The accompanying photograph is a face view of a carpet showing my new design.

The design consists of a representation in 15 which is shown the series of gem-work patterns having irregular stem-connections. These patterns have the appearance of underlying and being independent of a lattice or net work of cross-lines through the openings of which these 20 patterns are visible.

I claim—

The design for a carpet, substantially as shown and described.

WINTHROP L. JACOBS.
